MACHINE FOR SHAPING LEATHER BLANKS
INTO SHOE COMPONENTS SUCH AS TOE
CAPS

Alfred G. Gilbert, South Acton, and William H. Rogers, Jr., Malden, Mass., assignors to Reece Folding Machine Company, Woburn, Mass., a corporation of Maine

Application May 11, 1948, Serial No. 26,254

8 Claims. (Cl. 12—64)

1

This invention consists in a novel apparatus for producing shaped leather and like components of shoes or like garments or articles; a typical instance being the shaping of shoe toe cap pieces, composed of leather or simulations or substitutes therefor, of substantial thickness and therefore difficultly bendable, other appropriate materials including heavy and relatively resistant or stiff fabrics or felted goods. In the manufacture of such articles the conditions and problems presented are quite different from those presented in the handling of relatively thin and pliant leather, fabrics and the like which can be sharply infolded and creased for certain manufacturing operations remote from those of the art to which the present invention pertains.

The general object of the present invention is to afford an apparatus or machine, adapted to the performance of the operations to be described for the production of special components of shoes or other articles in a practical and efficient manner, to turn out such products or components well adapted to the further operations, including attaching or stitching into the shoe or other article, and capable of an output of high rate and moderate cost. A particular object is to afford the production of a shaped component such as referred to made from a cut blank of a relatively resistant sheet material as stated, the product having its margin, or usually only a portion of its margin, upturned and inbent to receive a predetermined curved outline as seen in face view, but with a substantial gap or open space between the body and the inbent margin of the component, in other words without any definite fold or crease therebetween; the component being then in readiness for incorporating into the manufactured shoe or article, as by conventional stitching means adapted to reach into the space between the component body and margin for thus attaching the component, along its rounded outline, to another component or components of the shoe or other article; a typical instance being the employment of the inbent component margin for the stitching of a shoe toe cap piece to sole elements of the shoe.

Another object of the invention is to afford a combination apparatus or machine, preferably automatic, and wherein successive steps or operations may be performed in one single cycle of action upon the entire blank, so that the blank may remain supported in a single location throughout the steps performed; thus distinguishing from a known method of preparing shoe and like components, requiring high skill and

2

close attention, which comprises holding a blank in the hand and manipulating it for its margin to travel progressively through a single shaping or bending point, accompanied by a step-by-step feed of the blank, analogous to the intermittent fabric travel produced in the use of a conventional hemming attachment on a sewing machine with its intermittent clamping and progressive feeding actions as the hemming proceeds.

10 Other objects and advantages of the invention will be explained in the description hereinabove presented or will be understood by those conversant with the general subject; and to the attainment of such objects and advantages the present invention consists in and the novel apparatus for producing shaped components of the kind described, and the novel features of operations, combinations, arrangements, constructions and details herein illustrated or described.

20 In the accompanying drawings, on Sheet 1, Fig. 1 is a perspective view of a blank of leather or like material cut out in this instance in a form suitable for a shoe toe cap piece, with a dotted line indicating the shaped partial outline of the completed component.

25 Fig. 2 shows in perspective, in a simple illustrative manner, the principles of an apparatus or cooperative combination of members, formplate, moldplate and inbender member, embodying the principles of the invention, with the parts in an initial position ready for operation upon the blank. Fig. 2a is a vertical sectional view taken longitudinally through the apparatus and blank of Fig. 2.

30 Fig. 3 is a perspective view similar to Fig. 2 but in a later stage of operation, the blank margin being upturned.

35 Fig. 4 is a view generally similar to Figs. 2 and 3 but in a still later stage of operation and certain machine members being indicated only in dotted outline to show more clearly the character of the completed component or shaped blank. Fig. 4a is a vertical sectional view similar to Fig. 2a but showing the parts in positions corresponding with Fig. 4.

40 On Sheet 2, Fig. 5, on an enlarged scale, is a perspective view of the completed component seen in Figs. 4 and 4a, after removal from the machine. Fig. 6 is a longitudinal sectional view 50 through the component taken on the line 6—6 of Fig. 5. In the blank of these figures the margin is bent inwardly and well down toward the body, but sprung up partly due to the difficultly bendable character and resilience of the leather material; the result being practically satisfactory for

manufacturing purposes, and even advantageous in facilitating access for stitching through the margin.

On Sheet 3, Fig. 7 is a top plan view of an automatic apparatus or machine embodying, and performing the operations of, this invention, the machine being shown with its formplate and carrier manually swung over, back and down into idle position, thus disclosing the underside thereof and better showing the other mechanisms of the machine; the machine being illustrated of duplex character in that in each cycle it can operate simultaneously upon a symmetrically reverse pair of blanks, to become mated components, as in a pair of shoes.

Fig. 8 is a righthand view of a detail of the formplate and mountings taken partly on the section line 8—8 of Fig. 7. Fig. 9 is a front elevation view of the parts seen in Fig. 8 in their operating position. Fig. 9a is a top view of the formplate per se and its integral extensions.

Fig. 10 is a front elevation view of certain of the pressure producing parts as embodied at the left end of the machine, seen partly also in Fig. 7.

Fig. 11 is a perspective view of an assemblage of certain upper parts seen also near the left end of Fig. 7.

On Sheet 4 Fig. 12 is a righthand elevation of the machine, partly in section on the line 12—12 of Fig. 7; while Fig. 13 is a similar section on the line 13—13, and Fig. 14 a partial rear elevation of certain parts of Fig. 13.

Fig. 15 is a righthand elevation on the line 15—15 of Fig. 7, and Fig. 16 is a partial rear elevation of certain parts of Fig. 15, Fig. 17 being a partial front elevation of other parts of Fig. 15.

Fig. 18 is a detached righthand view of certain details, while Fig. 19 is a top view thereof.

Fig. 20 is a diagram of the pressure applying and timing means.

The principles of the invention are adapted particularly to the marginal shaping (as distinguished from mere infolding and flat creasing) of various shoe or other blanks, especially shoe toe cap components, where the production of the final products presents the difficulties described.

The invention consists in apparatus for treating or shaping a pre-cut flat blank of difficultly bendable non-metallic sheet material to produce a component having a body of predetermined convex curvature, as seen in outline, with a shaped margin that stands up away from the body and thence extends inwardly spaced above the body, thus providing a substantial open gap between margin and body.

Describing first the blank B, Figs. 1 to 6, its body B' terminates forwardly in a tip end or apex B² and rearwardly in side wings B³, this outline being suitable for a toe cap piece for a ladies' shoe. In Fig. 1 is shown by a broken line B⁴ the bend line or final contour of the component, and between such contour and the outer edge is the initial flat margin M, seen also in its first position in Fig. 2, while Fig. 3 shows this margin at M' in its upturned condition, Fig. 4 showing the same margin at M² in its final inbent condition; while Figs. 5 and 6 show the completed component C after removal from the machine and with the inbent margin M² slightly reopened due to the resilient properties of the sheet material. The component C has its front apex or nose end C' of the desired contour, and Figs. 5 and 6 show clearly the space or air gap C² 70

between the inbent margin M² and the body B', there being no creased fold in the product.

Simple elements of apparatus for producing the shaped component, are diagrammatically illustrated in Figs. 1 to 4a. These parts include as the main elements a removable formplate 20, being the pattern or interior shaping member with contour of the final shape desired; a fixed moldplate 28, being the recessed exterior shaping member cooperating with the formplate in a first operation; a movable inbender or wiper member 33 cooperating with the formplate in a second operation; and a presser or member 37 to depress the bendplate forcibly upon the formplate. Preferably the blank B is set down initially upon the moldplate to be described, the formplate is moved down into the moldplate recess, the inbender plate is then moved in, and the press member caused to thrust down upon the bendplate, these actions being later reversed; but in using such or similar terms of direction or position this is for facility of description and not intended to constitute limitations upon the invention.

Completing the description of the implements which operate upon the blank, the formplate 20 has a convex contour 21 as seen in plan, see Fig. 2, with an apex or nose end 22 and an idle rear end 23 of straight or other convenient contour. As best seen in Figs. 2a and 4a the formplate has a relatively thick and rounded form of edge 24, as seen in section, precluding any sharp folding or creasing, while underneath the operative part of its margin the formplate is constructed with a distinct camber or convex curvature 25, its bottom face being curved upwardly away from a flat horizontal plane toward its edges, in preference to extending flatly throughout. This cambered structure permits the squeezing of the inbent margin portion M² between the formplate and inbender to compact and smooth it to its shape without any pressure on the blank body that might mar it and the final product. The formplate also has an upstanding shank 26 by which it may be mounted for lowering into forming position followed by upward retraction.

The exterior moldplate 28, see Figs. 2, 2a and others, is constructed with a contoured recess 29, corresponding closely with the desired outline of product, the recess being such that the formplate and blank can be relatively lowered into the recess as in Fig. 3, causing the first step in the shaping of the blank. Beneath the moldplate recess there is preferably provided a blank support 31 which may prevent the blank from descending entirely through the recess; and while such underneath support may be in the nature of a ledge or shelf projecting inwardly from the moldplate contour, it preferably consists of a separate supporting plate or raised pad upon which the moldplate is mounted in an interchangeable manner and which may be arranged to transmit heat and moisture to the blank under operation. The plate 31 is secured on top of a fixed bed 45 which may be hollow to receive steam for heating purposes.

The inbender 33, seen in all of Figs. 2 to 4a, is contoured at its inner edge concavely to correspond generally with the desired outline. As shown, the bender or wiper plate comprises a relatively heavy body portion 34 and a relatively thin bending edge portion or margin 35 of the desired contour. When the bender plate advances inwardly it bends over inwardly and

downwardly the upturned blank margin M' , well above the blank body level, forcing the leather smoothly upon the formplate top margin with a wiping action, later retracting the bender for removing the product. For so pressing the inbent blank edge downwardly upon the upper surface of the formplate there is provided a presser 37, being a device or member, or several thereof, which is mounted to be forcibly lowered upon the inbender, thrusting the latter smoothly against the inbent blank margin M^2 , and flattening the crimps that tend to form during the inbending. A swinging lever arm 38 carries each presser.

The operation may be more completely described as comprising the defining and starting the shaping of the edge contour of each blank B between the interior formplate 20 and a recessed exterior moldplate 28 by applying the formplate to the blank in a forcible way to thrust the blank into the recess 29 of the moldplate, thereby to upturn the margins M of the blank; the formplate having thick and smoothly rounded edges as seen in Fig. 2a adapted to define a shaped product the edges of which are not creased but between whose body and inbent margins remains a substantial airspace or open gap; and then by the exterior inbender member 33, which operates adjacent to the moldplate, while the blank and upturned edges remain held in position, forcibly bending such upturned margins inwardly over and down with a wiping action upon the upper edges of the formplate and confining them so; and thereupon applying supplemental pressure upon the inbender to press the inbent margins between the inbender and formplate, to complete smoothly the edge shaping of the component. In either aspect of the method it preferably comprises also the maintaining of the blank under heat and moisture during the described operations and, finally, relaxing the pressure and releasing the component from its engagement with the inbender, the formplate and the moldplate, permitting its removal from the apparatus and the insertion of a fresh blank.

As to certain portions of the apparatus not completely herein shown, such as the details of heating and moistening means, and the hydraulic system for forcibly lowering each presser 37, reference may be made to portions of co-pending application No. 597,190 filed June 2, 1945, which has subsequently matured into Patent No. 2,453,623 of November 9, 1948, relating to a different class and type of machine, for more detailed disclosure.

While the principle of the invention is indicated in the diagram Figs. 1 to 6, an example of actual structure is shown in Figs. 10 to 19, Fig. 20 being a diagram of the illustrative hydraulic mechanism and operation for thrusting downwardly the pressers to perform the final step of smoothing and compressing the inbent margin portion M^2 of the shaped blank. It is therefore convenient to make reference to certain general parts of the apparatus or automatic machine, at this point.

The upright general frame comprises a number of fixed parts including upright end walls 40 between which extends the main shaft 41, being preferably a cyclic shaft, making one turn per operation, and carrying cams for effecting the timed actions of the apparatus, particularly the lowering and lifting of the formplate 20 into and from position and the inward and outward

movements of the inbender or wiper plate 33 and the operative depression and release of the presser members 37. Extending upwardly from the frame walls 40, at the rear, are brackets 42, upon which a rear axle 43 is mounted, either fixedly or with rocking movement, in connection with the lowering and lifting of the formplate. Another main frame part is a central longitudinal table 44 supported in level position upon the end walls 40. Supported above said table is the operating bed 45 of the machine, which it is usually preferable to maintain heated, such bed being hollow to afford a steam chamber 46, supplied with heating steam in a conventional manner, not fully shown. In cases where it is desirable to have a duplex heating system the bed 45 may be provided also, embodied in its top wall, with a series of electrical heating units 47, energized through a heater control box 48. The resistance units 47 may be accommodated in grooves in the steam chest top wall, and confined by an overlying cover plate 49, above which is attached the blank supporting plate 31 on top of which each blank is held throughout the described shaping operations.

Referring next to the pressing system, this comprises preferably a plurality of the fingers or thrust pins 37 each carried upon its swinging arm 38 to swing downwardly and upwardly. The details appear in Figs. 7 and 10 and in the diagram Fig. 20. Each presser arm is secured by a clamp 51 to a rocker 52 which may consist of a cradle with tilting end cheeks. As shown, a single clamp 51 serves for two presser arms, both being held by the clamp, and the clamp being held between two of the rocking cheeks 52, the latter being pivoted at 53 near the front and back of the blank support 31, upon stationary lugs or fixtures 54. Normally the presser pins stand somewhat elevated above the levels of the formplate and the inbender, the lowering of the pressers occurring only after the inbenders have shaped the blank margins over the formplate. The apparatus having two sets of inbenders, one at each end of the bed, a single one of these may be considered in described the pressing structure and operation. Each rocker 52 not merely carries the clamp which adjustably holds the presser arms 38, but also has an outward extension beyond the bed 45. To maintain the presser pin normally elevated this rocker extension is shown pulled downwardly by an elongated spring 55 whereas, to thrust downwardly the presser there is provided a rod 56 arranged to press upwardly on the outer extension or arm of the rocker. Any timed means of exerting powerful elevation or swing to the rocker will serve for pressing purposes, a hydraulic system being shown as a preferred example. Thus, the lower end of the rod 56 can be pressed upwardly by a piston 57 which slides in a cylinder 58 mounted in a fixed position upon an end frame part of the apparatus. These parts are well shown in Fig. 10. Passing next the diagram of Fig. 20 it is seen that the necessary pressing force is provided by a cam 61 on the main shaft 41, the cam having a rise and a drop between two dwells, so that its follower 62 swings rearwardly and forwardly at separated points in each cycle, with pauses between. The follower 62 is placed on the first arm of a bell crank lever 63 pivoted at 64, its other arm being pivoted at 65 to a pitman 66 by which the motion is transmitted to a piston 67 operating in a hydraulic cylinder 68, this couple constituting a hydraulic forcing

means for operating all of the pressers of the apparatus, with an equalizing action. The interconnection between the hydraulic motor 67, 68 and the first mentioned piston and cylinder device 57, 58, is through a system of communicating and distributing tubes 69, each of which may be flexible, and which extend to the cylinders through which the several presser devices are actuated. To keep the system charged with liquid, as is necessary to transmit the full force of the cam, there is provided a liquid supply vessel 70 of conventional character, which is closed off automatically with each advance of the piston 67. The liquid L may be a conventional light oil.

The presser actuation has been indicated. The cyclic cam 61, turning counterclockwise in Fig. 20, has just released the hydraulic pressure thereby to remove the mechanical pressure of the presser pins 87 from the inbender 33, the restoring spring 55 lifting the presser slightly to clear the inbender. After a prolonged dwell, during which the formplate and inbender are put through their operations, the rise of the cam 61 comes into play, at a point of time when the formplate and inbender have reached their position shown in Figs. 4 and 4a. The cam rise causes the bell crank 63 to thrust inwardly the piston 67, which piston is normally held retracted by spring means, such as the spring 71 immersed in the hydraulic liquid L in the cylinder 68. This use of the open type of cam 61, with spring means holding the follower to the cam, is preferred instead of using a closed type of cam. The liquid storage or supply in the vessel 70 is preferably at a high level, to afford a pressure head, or the vessel is maintained under internal air pressure for the same purpose, so that, while the piston 67 stands retracted liquid flows into and fills the system comprising the cylinder 62, the distribution tubes 69 and the cylinders 58 of the several hydraulic couples which transmit the force mechanically for the forcible lowering of the pressers. As soon as the piston 67 starts its advancing motion it closes off the port or passages between the vessel 70 and cylinder, and thereafter applies the necessary force to the liquid to produce the hydraulic and mechanical actions described.

Returning to the formplate 20 this will here be described in respect to its mountings for its down and up movements and the timed connections therefor, and the introduction of a special feature by which duplex actions and results are conferred upon the mechanism, as indicated in the bottom view at the upper part of Fig. 7, with details illustrated in Figs. 8, 9 and 9a, Fig. 12 showing the same in right-hand elevation. The novel duplex arrangement referred to has two distinct aspects which are cooperatively embodied. The first aspect is that a matched pair of formplates 20 is used, designated 20L and 20R, see Fig. 7. These two formplates are arranged back to back with what may be called their primary or active convex contours 21^a and apexes 22^a directed outwardly or away from each other, so that when these formplates are lowered upon the blank support 31 they will lie upon and define the contours of two separate toe cap blanks B which, after completion, constitute a L and R pair of components adapted to be embodied in a lefthand and a righthand shoe respectively. Both of such blanks thereby become shaped simultaneously, as indicated in Fig. 7, there being corresponding inwardly directed moldplates and

inbenders for the two formplates. The matching completed products when taken from the machine are early subjected to the stitching operation by which these toe cap components are interconnected with adjacent components of a pair of shoes.

The second aspect, also embodied in the illustrated apparatus, is that each of the two formplates, 20L and 20R, without detachment from the machine, is readily shiftable or reversible so as to interchangeably put into effect the aforesaid primary contour 21^a, 22^a or, at will, to change over to a different secondary contour 21^b, 22^b, shown, but out of operation, in Fig. 7, which may be serviceable for a difference in size or a difference in style of the toe cap component. Each of the paired formplates may thus be reversed in the machine by a rotary action and setting, to be described. It is convenient to lead up to such point of description by commencing with the general features of the formplate mechanism.

For the lowering and lifting movements of the formplate system, whether single or duplex, there is shown a swinging carrier 74 consisting of side arms connected by a cross web, the whole extending to where the carrier has hubs 73 preferably fast upon the axle 43. At the free or front swinging end of the carrier 74 there is formed an enlargement or swinghead 75 consisting of several rigidly united parts, as follows. There is a pair of bosses 76 in which are mounted right and left drop rods 77, seen in Fig. 12 as depending from the bosses, and these rods at their lower ends carrying a longitudinal beam 78 below which the formplates are mounted as will be described; said beam at its underside being formed with a shallow longitudinal groove or slot 79 taking part in the mounting and positioning of the formplates. On the axle 43 is shown a third hub 82 which has an offset extension 83 serving as a stop member and adapted to contact against a fixed stop member or lug 84 when the carrier 74 has been manually swung up and over rearwardly and downwardly to the inverted position shown at the upper part of Fig. 7, as for access or repair.

For the regular actuation of the formplate carrier to swing downwardly and upwardly as between the full-line and dotted positions shown in Fig. 12, the carrier is provided with a toe or short lever arm 85 projecting from one of the hubs 75 at a downward rearward slant. The swinging forward of toe 86 causes lifting of the carrier and formplates. To effect such actuation there is shown a long link 87 the rear end of which is pivoted by a pin 85^a to a radius arm 85 loose on axle 43. The pin projects into the path of the toe 86 and thus affords a loose coupling to the toe. The front end of the link is guided to permit its fore-and-aft lengthwise movements. Such guidance may be by means of a cutaway or lengthwise slot 88 in the link separating its widened portion into the two side parts of a fork or yoke, which straddles a fixed collar or guide 89 formed for example on the cam shaft 41. Said collar may be the hub of an operating cam 90, which therefore turns with the shaft, making a complete turn in each cycle. The action of the carrier lifting cam 90 is transmitted to the link 87 by means of a follower 91 consisting of a roller mounted at the extreme front end of the link and engaging or bearing upon the cam. The cam contour has one long dwell and opposite to it a short dwell, these being

connected by a steep rise and a steep drop, the rise of the cam corresponding with and causing the lifting of the carrier and formplate mechanism, and vice versa, the lowering force being gravity.

By the described formplate swinging arrangements and the cyclic timing thereof the formplates remain in their lowered operative position for the greater part of each cycle; but after the shaping of each blank has been completed and the inbender 33 has been retracted the formplates and carrier swing rapidly upwardly, e. g. to the retracted position shown dotted in Fig. 12, either stopping or pausing slightly at their top position for the removal of the products from the formplates, thereupon descending quickly again to operative position after a new pair of blanks has been inserted upon the moldplate 28 and blank support 31 as already described. The cam shaft may be driven under manual or pedal control, as through a clutch and brake mechanism, not shown, for example to afford an automatic stoppage at the end of each cycle when the carrier and swinghead are at the high point of their cam-produced lift; and there may be an intermediate stop at that point when the presser mechanism is in full action, permitting the pressing period to be prolonged at will, as in special cases, before resuming operation.

Referring again to the mountings of each formplate 20, it is unitary with its shank 26 which is supported by the beam 78. For purposes of style-change reversal the shank can be turned 180° in a vertical bearing hole extending through the beam. As shown, the formplate has a central elevation or pedestal 94, which in turn has a longitudinal rib 95, upward from which extends the shank 26; Fig. 9a being a top view of these unitary parts, rotatable on the beam. The rib 95 normally engages the groove 79 in the underside of the beam, holding the formplate rigidly in place. For reversal, at will, the shank and carried parts may be lowered, permitting rotation by shifting the rib below the groove. This is resisted by a yielding means or spring 97 on the shank, confined above the beam and below a collar 98 on the upper part of the shank. For manipulation the shank carries a reversing handle 99, being an arm projecting laterally from the shank.

By these devices the two formplates can be reversed without detachment, in a matter of seconds, by grasping the handle arms, one in each hand, depressing them to release the ribs 95, swinging them 180° and allowing them to rise as the ribs snap back into the beam groove 79. Naturally the inbenders 33, one cooperating with each of the formplates, right and left, may have concave bending contours corresponding with the convex contours of the formplates, and reversing mechanisms for quick change, as will be described.

Referring to the optional plan of heating the implements which act upon the blanks, and moistening the blank, to improve the shaping operations, each of these acts may be performed by the use of steam. The details of steam flow and distribution need no description but there is shown a steam supply pipe 101 with an extension 102 to the steam chest 46 and an extension 103 to a means or jets to spray the blank margin at certain points in the cycle, under control of a cam-timed valve 104. A descending pipe 105 drains condensate away. Such plan of heating

or moistening or both is not per se herein claimed.

As shown in Figs. 7, 11 and 13 to 17, the inbender or wiper plate element 33 of the apparatus, like the formplate, is provided as symmetrical duplicates 33L and 33R each having a primary concave contour 36^a shown in operative position and a secondary such contour 36^b, shown in idle position. When the pair of formplates or formers 20L and 20R is lowered upon the blanks B upon the support 31 the formers stand between the longitudinally retracted inbender plates 33L and 33R, in such relation that the subsequent advance of the inbenders turns the upstanding blank margins inwardly upon the top sides of the formers. For this purpose the inbender system is arranged and connected for such inward and outward longitudinal bending movements. Also a short bodily lift and descent of the inbender system is provided to cause sufficient elevation of the inbenders that on their inward movements they may rise slightly above the top faces of the moldplates 28 and so ride up upon the blank margin portions M² to inbend and wipe them on to the top surfaces of the formplates.

These inbender movements, inwardly and outwardly, and upwardly and downwardly, shown by comparing Figs. 2a and 4a, are herein produced automatically under cam timing, as will be described, coordinated with the downswinging and later retraction upwardly of the pair of formplates; these motions being coordinated also with the described presser system, the pressing of the bends by the depression of the inbenders taking place after the latter have been moved inwardly over the edges of the blanks and formplates, the pressers being retracted again before the outward retraction of the inbenders. In addition to these coordinated actions the inbenders are mounted for symmetrical reversal of each of them by manual means, to be operated at the time when the formplate reversing handles 99 may be operated, to change the inbenders, by 180° of rotation, to present the secondary concave contours of the inbenders for cooperation with the reversed formplates.

The description of the apparatus involved in such functions may well begin with one of the active connecting parts taking part in the two pairs of inbender motions described. There is shown an elongated longitudinal carriage member 110, in the form of a substantially square bar, with top side dovetail ribs, and underneath recesses 109, as shown in Figs. 7, 11 and 13 to 15. This carriage is shown to the rear of the blank support 31 and is adapted to be moved bodily fore-and-aft and up and down, to produce in the inbender system the described longitudinal in and out and the slight lifting and lowering thereof. Dovetailed on top of the carriage 110 are left and right adjusting blocks 111, one for each of the inbenders. These blocks may each be adjusted slidably along the carriage, and a set screw 112 is shown in Fig. 13 as a means for fixing the adjustment. One of the mechanical elements carried on and partaking of the movements of the carriage is a frontwardly projecting actuator bar 113, one such bar being mounted by a spacer plate 114 on top of each of the adjusting blocks 111. The operations caused by said actuator bar and by other connections from the adjuster block will be described later, after describing the mechanics of the means for pro-

ducing in the carriage its front and back and its up and down motions.

For producing the front and back motions of the carriage 110 there is shown in Figs. 13 and 14 a cam disk 115 on the main shaft 41, this cam having a groove 116 which is engaged by a follower or roll 117 mounted at the free end of the first arm 118 of a bell crank lever whose second arm 119 extends vertically, this lever being fulcrumed at 120, such fulcrum being shown as an elongated rod mounted in the lower part of an elongated double bracket 121. The second arm 119 of the bell crank is shown as forked to provide longitudinally spaced connections to the carriage. A link 123 extends from the top end of each branch of the forked arm to the head or block 124 of a slidable rod 125 mounted in the frame table 44. These two heads 124 each carry an upstanding shoe member 126 which extends into the underneath recess 109 of the carriage, as seen in Fig. 13. The action of the cam therefore is that the two shoes, near the ends of the carriage, reciprocate rearwardly and frontwardly, and thereby shift the carriage accordingly with a true and parallel movement.

To impose upon the carriage 110 its slight lifting and lowering movements it is provided, near each end, with a depending contact lug 129, and these carriage contacts 129 are engaged underneath by a pair of swingable fingers 130, each extending from a hub 131 on a shaft 132. See Figs. 15-17. For true parallel movements these parts are duplicates; and at the front end of each shaft 132 is mounted a cam arm 133, preferably at the front of the table 44. Each arm 133 extends downwardly and carries a follower 134 which engages a cam face or surface 135 at the side of a cam disk 136 which is mounted on the main shaft 41. The cyclic operation of the two cams 136 therefore causes the parallel lifting and lowering movements of the carriage. For initial adjustment between the cam arm 133 and the cam surface 135 there is provided an adjusting screw device 138, by which the position of the follower 134 at the free end of the arm may be adjustably shifted, affording a delicate means of predetermining the raised and lowered positions of the carriage.

The duplex arrangement of the inbenders has been referred to, both in the first sense that there are two inbenders 33L and 33R corresponding to the left and right formplates; while below each inbender is a corresponding moldplate 28L or 28R these having the concave formation at their inner but not at their outer edges. See Fig. 7. Both of these members 28 and 33 are generally square, except for their concave outlines, and when the inbenders are retracted they overlap and correspond closely with the moldplates beneath, as well shown in Fig. 11. The moldplates do not partake of the inward and outward movements of the inbenders. The latter are provided with shallow upstanding gage members 140 useful for the initial positioning of the blanks, in the manner indicated in Fig. 2, wherein the inner edges of 28 and 33 substantially correspond, having the effect of a thickened moldplate, but the upper member, the inbender in each case, being thereafter operated as described to rise slightly as seen in Fig. 4a and shift inwardly beyond the moldplate to inbend the blank margin. This arrangement has the importance that when operations start the inbender lies under the blank margin so that, when the margin has been turned up as shown in Fig. 2a in dotted lines, the in-

bender can bend over the upstanding margin on to the top surface of the formplate.

For the purpose of manipulating the moldplate it is shown provided at its outer side with an upstanding post 141. The moldplate at each end, and the inbender superimposed thereon, may both be positioned and guided for longitudinal movements with their edges beneath a pair of front and back guides or side ledges 142. For the purpose of affording the 180° reverse rotation of each inbender it is bodily removable from under the guiding ledges 142. By such removal or disengagement of the inbender it may then be turned end for end and replaced for the changed size (or style) of blank.

An important element in the described mechanism is an oblong floating base or block 143, through which the inbender shank 154 extends upwardly as does the formplate shank 26 in the beam 78. Said block or float has a short frontward extension to which is attached an upwardly and frontwardly extending handle 144. When the mechanism is once set for the inbending of a given style each float or base 143 constitutes a means for performing several functions, including transmitting longitudinal movements inwardly and outwardly, to its inbender. To transmit such movements from the carriage 110 to the block or base 143 and thereby to the inbender, the actuator bar 113 projecting from the carriage is formed with an open slot 145, see Figs. 7, 11 and 13, engaged by a pin 146 projecting downwardly from the longitudinal arm 147 of a bell crank lever, which has its second arm 148 extended frontwardly, this two-armed lever being fulcrumed on a vertical axis by an upstanding post 149 fixed to the top side of the bed 45. At its front end the second arm 148 is formed with a wide slot 151, which accommodates snugly the oblong floating base piece 143. By these connections, when the carriage 110 shifts frontwardly and then rearwardly, the bell crank 147, 148 converts such motion to a longitudinal swing which, acting through the base piece 143, causes the endwise shift inwardly and then outwardly of the inbender, thus accomplishing the primary purpose of the disclosed mechanism.

For a purpose to be explained the slot 151 of the arm 148, while substantially a closed slot, is connected with an opening or gate 152 at its longitudinally inner side, this gate being wide enough for the shank 154 of the formplate, upstanding from its pedestal 153, see also Figs. 13, 18 and 19, to pass longitudinally from the slot and through the gate, when the block 143 has been lifted above the level of the bellcrank arm 148. This permits the associated inbender and floating base to be disengaged bodily from their mountings, including the guides 142, by a longitudinally inward motion.

The floating block and inbender, as a unit, are now in hand, and the latter may readily be rotated 180° to change from its primary to its secondary contour, followed by the reengagement of the inbender with its mountings. These manual operations are facilitated by the handle 144 already mentioned, extending from the front part of the floating block frontwardly into easy access, and by this handle the floating block may be lifted, in the manner already described, above the level of the bellcrank lever, so that it clears the slot 151, leaving only the shank 154 of the inbender occupying the slot, the gate 152 being sufficiently wide for the disengaging shift of these elements from their operating

connections. As already stated, the upstanding shank 154 of the inbender passes through a vertical hole in the floating block. At the upper part of said shank, well above the floating block, the shank, at its top end, is provided with a frontwardly extending handle 155 for manipulating these parts in cooperation with the manipulation of the block by the handle 144. In order to hold the inbender slightly elevated above its lowermost position, and preferably in contact with the underside of the floating block, its shank is provided near its upper end with a collar 156, spaced well above the block, and a coil spring 157 is interposed between the block below and the collar above. By these means the detachment of each inbender from its operating connections in order to reverse it 180° and restore it is readily effected; the operator grasping the floating block handle 144 with one hand and the somewhat higher inbender handle 155 by the other hand, and first lifting the block by the first handle until the block is entirely above the bellcrank, while compressing the spring and holding down the inbender by the second handle, thus positioning the inbender shank to pass through the gate 152. This entire assemblage is thus removed inwardly, whereupon, holding steadily the first handle, the second handle is thrown around through 180°, thus reversing the inbender outline, the parts being then restored by reversing the order of these operations. The float or block thus eventually takes its operative position within the bellcrank slot 151, and operations can then be resumed, to inbend blanks of the secondary style contour, when the formplate and moldplate have been suitably converted.

As already explained, each inbender 33 is to be lifted slightly relatively to the formplate and moldplate to facilitate its inward or bending movement as indicated in Figs. 2a and 4a; and such lifting and lowering movements of the inbenders are transmitted thereto by the corresponding lifting and lowering of the carriage 110. For these purposes each of the adjustable blocks 111 on the carriage has attached to it a plurality of lifting bars 160, extending frontwardly to positions beneath the inbender to be lifted. See Figs. 7, 11, 13, 15 and 18. The two lift bars 160 shown for each inbender partake of the carriage lift, which they transmit to the inbender, and they partake also of the frontward and rearward transverse movements of the carriage, although these are idle motions in the lift bars.

For the purpose of transmitting the lifting and lowering movements of each inbender 33, without any interference with the blank supporting pad 31 or the moldplate 28, the following structure is provided. Each of the two lift bars projects frontwardly into a space provided by a top groove 161 in the fixed plate 49 and a matching underneath groove 162 in the blank support. These grooves or cutaway portions provide a deep recess which is open at its rear end and is of extended vertical dimension to permit the lifting and lowering movements of the bars 160.

Such lift bar rising and lowering movements are transmitted to the inbender 33 by means extending upwardly from the inner end of each of the lift bars through registering holes 165 formed both in the supporting pad 31 and in the overlying moldplate 28, and reaching to the inbender plate thereabove. This transmitting device is shown as a member 164 having up-

standing fingers 165 which reach through the holes in the pad and moldplate into lifting contact with the inbender. These parts are best shown in the sectional view Fig. 18 and the top view Fig. 19. The member 164 may be considered a lift finger member, and its lower portion preferably lies flatly on top of its lift bar 160, resting loosely thereon rather than being attached, so that the front and back horizontal movements of the lift bars will be idle sliding movements having no effect upon the lift finger action. The inbender normally rests down upon the moldplate, as in Fig. 2a, and when the carriage and lift bars are in their lowered position the member 164 and its upstanding fingers 165 rest down upon the lift bars, with their top ends preferably slightly below and out of contact with the underside of the inbender. When, however, at the proper point in the cycle, the carriage rises, the lift bars raise the lift member, and its fingers thereby cause the lifting of the inbender from the Figs. 2a to the Fig. 4a position. There being two of the lift bars, and each of them carrying two lift fingers, four points of lift are provided, giving an even and parallel motion to the inbender, the top of which motion is preferably limited by the overlying guide ledges 142. The desired objective has thus been attained by the described inbender lifting and lowering mechanism actuated from the rear carriage.

The operative movements of the active members 20, 33 and 37 have hereinabove been described, along with the mechanisms for producing their movements, all timed from the main shaft 41. The formplate 20 is lowered by its cam 99 after a blank has been laid in position, manually or otherwise, with its margin overlying the inbender 33, thus resulting in the upturning of the margins as shown in Figs. 2a and 3, the moldplate 28 taking part in this first shaping step. The inbender is then lifted slightly as in Fig. 4a and advanced inwardly to inbend the blank margin over the thick formplate edge; these respective movements being produced through the carriage 110 by means of the lifting cam 136 and the other cam 115, with relative timing as indicated. Thereupon the presser 37 is operated from its cam 61 to depress forcibly the inbender, especially at the inner edge thereof, to press, flatten and remove crimps from the portion of the blank margin overlying the flat top side of the formplate. Thereafter, the cam 61 relaxes the pressure and lifts the presser, the cams 115 and 136 move outwardly and then lower the inbender upon the moldplate, and finally the cam 99 swings to its elevated position the formplate, carrying the completed product, which may then be removed manually or otherwise. For quick interchange of the machine for differences in size or style it has been described how a duplex formplate may be used, with two different outlines, and manual means for shifting or rotating the formplate to bring either the primary or secondary outline into operative position; the description disclosing also how each inbender plate may similarly be rotated to change correspondingly from a primary to a secondary outline.

It has not yet been described how the moldplate 28 may be analogously changed to a different outline, when required, although, as may be seen in Fig. 2a, a single moldplate may serve for several different sizes or styles of product in view of the fact that the inbender plate overlies the moldplate and has the required outline oper-

15

able to upturn the blank margin as the formplate is thrust downwardly upon the blank. A simple and practical mode of interchange for the formplate, by use of the mechanism already described, is as follows. When the inbender in its sub-assembly with the floating block 143 is detached, as described, for reversing the inbender to 180° to change its contour, the moldplate at this time, before the reattachment of the inbender, may readily be slid out from beneath the guiding ledges 142 and thus completely detached, to be replaced by a substitute moldplate having an outline to correspond with the secondary outlines of the formplate and inbender. These manipulations of the stationary moldplate, for interchange purposes, are readily effected by the moldplate upstanding handle 141, appearing in Figs. 7 and 11. In order to anchor stationarily the moldplate after interchange a simple positioning device may be employed, such as a pair of spaced apart pin-and-hole devices 170, Fig. 7, small holes being formed in the moldplate in position corresponding with small pins upstanding from the blank supporting pad 31.

There have thus been disclosed an apparatus for producing shaped leather and like components of shoes or like garments or articles which embody the principles and attain the objects of the present invention; but since many matters of operations, combinations, arrangements, constructions and details may be variously modified without departing from such principles, it is not intended to limit the invention to such matters except to the extent set forth in the appended claims.

What is claimed is:

1. A machine for shaping pre-cut blanks of leather or like difficultly bendable material into toe cap or like components of shoes or like articles comprising, in combination with a support for the blanks to be shaped, an interior formplate having a convex forming outline of thick and rounded edge section, with mountings determining and guiding lowering and rising movements toward and from the blank support; an exterior moldplate upstanding above the support level and recessed to a form to surround and correspond to the outline of the formplate, so that when the formplate is lowered it thrusts the blank into such recess thereby to shape the blank body and upturn its margins; an inbender or wiper plate movable above said moldplate and having an operative outline corresponding to that of the formplate, with mountings determining and guiding inward bending and outward return movements thereof, thereby to inbend and wipe the upturned blank margins snugly over the thick edges of the formplate; a supplemental presser means mounted to be lowered upon the inbender in its inward position thereby to squeeze the inbent blank margins between the inbender and the top side of the formplate; and timed operating mechanism adapted in each cycle to actuate said formplate, inbender and presser in coordination; and said machine, above the blank support, having, in addition to such formplate, a second such formplate, the two thereof being of symmetrically mated contours, lowerable by said formplate mountings to the middle part of the blank support; and having outwardly thereof, in addition to such moldplate, a second such moldplate, the two thereof being arranged with the respective formplates between the same and corresponding in outline therewith; and above said respective moldplates, in addition to such

16

inbender a second such inbender; the two thereof corresponding in outline with said formplates; said formplate and inbender sets or pairs being actuatable in unison to shape two mated shoe parts in each operation, for left and right shoes respectively; and said machine having its said formplates constructed each with two different shape outlines and having mechanisms for convertibly shifting, without removal from their mountings, the two formplates to bring one or the other of such outlines at will selectively into active position.

2. A shaping machine as in claim 1 and wherein in each inbender has mountings convertibly shiftable at will as between two outlines corresponding to the outlines of the formplates.

3. A shaping machine as in claim 2 and wherein in the conversion of formplate and inbender as between different shapes is adapted to be effected by rotation on the mountings thereof by substantially a half-turn.

4. A machine for shaping leather blanks into shoe components, as toecaps, comprising a reversible formplate member having primary and secondary forming outlines of thick edge section, with mountings and means to cause lowering and rising movements toward and from the blank shaping position; a moldplate recessed to cooperate with the outline of the formplate, such that when the formplate is lowered it thrusts the blank into such recess thereby to shape its body and upturn its margins; and a reversible inbender member above said moldplate having primary and secondary outlines cooperative with the outlines of the formplate, with mountings and means to cause inward bending and outward return movements thereof, thereby forcibly to inbend the upturned blank margins snugly over the thick edges of the formplate.

5. A machine for shaping leather blanks into shoe components, as toecaps, comprising a reversible formplate member having primary and secondary forming outlines of thick edge section, with mountings and means to cause lowering and rising movements toward and from the blank shaping position; a moldplate recessed to cooperate with the outline of the formplate, such that when the formplate is lowered it thrusts the blank into such recess thereby to shape its body and upturn its margins; and a reversible inbender member above said moldplate having primary and secondary outlines cooperative with the outlines of the formplate member, with mountings and means to cause inward bending and outward return movements thereof, thereby forcibly to inbend the upturned blank margins snugly over the thick edges of the formplate; at least one of said members having a spring-pressed shiftable shank, and being mounted thereby in a manner with the member normally locked but adapted to be unlocked by shifting its shank to permit reversal of the member.

6. A machine as in claim 5 and wherein it is the formplate member that has such mountings to permit unlocking and reversal.

7. A machine for shaping leather blanks into shoe components, as toecaps, comprising a reversible formplate having primary and secondary forming outlines of thick edge section, with mountings and means to cause lowering and rising movements toward and from the blank shaping position; a moldplate recessed to cooperate with the outline of the formplate, such that when the formplate is lowered it thrusts the blank into such recess thereby to shape its body

and upturn its margins; and a reversible inbender above said moldplate having primary and secondary outlines cooperative with the outlines of the formplate, with mountings and activating means to cause inward bending movements and outward return movements thereof, thereby forcibly to inbend the upturned blank margins snugly over the thick edges of the formplate; and characterized further in that the said inbender mountings which permit it to slide in and out, are guide means permitting up-and-down motion and permitting detachment bodily endwise of the inbender from the guide means; together with the said actuating means the same including a slotted arm for causing such in-and-out sliding of the inbender; the inbender having an upstanding shank, a floating block occupying the slot of said slotted arm thereby transmitting the arm motion to the inbender through said shank, the latter being extended upwardly through a hole in said block; a collar on the inbender shank above the floating block and a spring between the collar and block tending to lift the shank and inbender relatively to the block, so arranged that the block may be lifted above the slotted arm while holding down the shank and inbender, said arm being provided with a gate leading from said slot and permitting the inbender shank to pass through the gate for bodily detachment of the inbender and block assembly; whereby the inbender may be rotatively reversed for outline conversion and reattachment in operative position.

8. A shaping machine of the kind described having a reversible formplate, and cooperating therewith a recessed moldplate and a reversible inbender, said inbender being mounted to slide in and out, with guide means permitting up-and-down motion and permitting detachment bodily endwise of the inbender from the guide means; together with actuating means including a slotted arm for causing such in-and-out sliding of

the inbender, the inbender having an upstanding shank, a floating block occupying the slot of said slotted arm and transmitting the arm motion to the inbender through said shank, the latter being extended upwardly through a hole in said block, a collar on the inbender shank above the floating block and a spring between the collar and block tending to lift the shank and inbender relatively to the block, all so arranged that the block may be lifted above the slotted arm while holding down the shank and inbender, said arm being provided with a gap or gate leading from said slot and permitting the inbender shank to pass through the gate for bodily detachment of the inbender and block assembly; whereby the inbender may be rotatively reversed for outline conversion and reattachment in operative position.
